UNITED STATES PATENT OFFICE.

HORACE G. JOHNSTON, OF CORSICANA, TEXAS.

HOISTING MECHANISM.

No. 833,462.

Specification of Letters Patent.

Patented Oct. 16, 1906.

Application filed April 19, 1906. Serial No. 812,678.

To all whom it may concern:

Be it known that I, HORACE G. JOHNSTON, a citizen of the United States, residing at Corsicana, in the county of Navarro and State of Texas, have invented certain new and useful Improvements in Hoisting Mechanism; and I do hereby declare the following to be a full, clear, and exact description of the invention, such as will enable others skilled in the art to which it appertains to make and use the same.

This invention relates to hoisting devices for well construction, and especially for use in connection with oil-wells.

15 The object of this invention is to provide a hoist embodying improved means for imparting a change of speed to the hoisting device.

A further object of the invention is to provide a sand-reel adapted to be placed upon 20 the hoisting-shaft and to be removed therefrom.

With this and other objects in view the invention consists of certain other novel constructions, combinations, and arrangements 25 of parts, as will be hereinafter more fully described and claimed.

In the drawings, Figure 1 is a perspective view of the improved hoisting device. Fig. 2 is a view of the hoisting device in side elevation. Fig. 3 is a view of the hoisting device in end elevation as seen along the arrow 3. Fig. 4 is a diametrical sectional view of the sand-reel used in combination with this machine.

35 Like characters of reference designate corresponding parts throughout the several views.

In its improved embodiment the device forming the subject-matter of this application comprises the usual frame 10, erected in any approved manner and upon which is journaled a driving-shaft 11, as by the pillow-blocks 12. The driving-shaft 11 is provided adjacent its middle point with the stepped sprocket presenting the sprocket-disks 12' and 13. The shaft 11 is operated from any approved source, as the conventional engine 14, provided with the power-shaft 15, upon which is mounted a stepped sprocket presenting the disks 16 and 17, the disk 16 being in alinement with the disk 13 and the disk 17 in alinement with the disk 12'. Upon the two stepped sprockets is mounted a sprocket-chain 18, said sprocket-

ets being of such diameter relative to each other that the said chain 18 will operate without change of length upon the sprockets 13 and 16 or the sprockets 12 and 17. Below the shaft 11 is journaled a reel-shaft 19 and operated from the shaft 11 by means of a sprocket-chain 20, passing over the sprocket 21 upon the shaft 11, and a sprocket 22 upon the shaft 19, and through the medium of a clutch 23 upon the said shaft, which is operated by the lever 24. The shaft 19 is provided with the usual hoisting-drum 25 and brake-disk 26, upon which is operatively mounted a brake-band 27, operated by the lever 28.

At one end the shaft 19 is extended, and thereon is mounted a sand-reel 29 of any approved form, but preferably comprising a hub 30, provided with a sliding key 31 and with peripheral flanges 32, upon which are secured annular disks 33 in any approved manner, as by the rivets 34, and forming the ends of the sand-reel.

The sand-reel by reason of the key 31 is arranged to be removably placed upon the shaft 19 when required for use and to be removed therefrom when a sand-reel is not required.

In operation it is found desirable to impart a different speed to the hoisting-drum when raising the apparatus from shallow or deep wells, for which purpose the stepped sprockets, as above described, are applied to the driving-shaft and to the engine-shaft.

Instead of removing the hoisting-cable from the hoisting-drum and applying the sand-cable thereto, as is usually done, the present invention embodies the removable sand-reel, which when not in use may be removed from the reel-shaft and laid to one side for use when required.

I claim—

1. In a device of the class described, the combination with a driving-shaft, of a stepped sprocket mounted upon said shaft, a power-shaft provided with a coacting stepped sprocket, a reel-shaft, means for rotating the reel-shaft from the driving-shaft and a removable sand-reel mounted upon said reel-shaft. 95

2. In a device of the class described, a driving-shaft, a stepped sprocket mounted upon said shaft, a coacting stepped sprocket positively driven, means connecting the two 105

stepped sprockets, a bearing, a reel-shaft journalized in the bearing adjacent the driving-shaft and extended at one end beyond the reel and the bearing, means for driving the reel-shaft from the driving-shaft, and a sand-reel removably mounted upon the extended end of the reel-shaft.

In testimony whereof I affix my signature in presence of two witnesses.

HORACE G. JOHNSTON.
